FEEDING AND ASSEMBLING OF ELECTRICAL TERMINAL PART OF WIRE

Walter E. Straubel, Johnston, R.I., assignor to Electric Terminal Corporation, a corporation of Rhode Island

Filed Aug. 30, 1960, Ser. No. 52,906

5 Claims. (Cl. 226—64)

This invention relates to a mechanism for feeding terminals and attaching a wire to such terminals for electrical purposes.

The terminals which are prepared for attachment to the ends of electrical wires vary from time to time as to their spacing, when in strip form, and frequently a feeding mechanism must be adjusted for positioning the terminals relative to the attaching mechanism. Sometimes overtravel may occur or adjustments of the plunger may be desirable with relation to variations in the work operated upon. It is also of advantage to view the operation of the mechanism upon the terminals.

One of the objects of this invention is to provide a feeding mechanism which may be adjusted very accurately as to its engagement with the work for feeding the same.

Another object of this invention is to provide a feeding mechanism, the stroke of which may be easily adjusted so that should the terminals vary in size or spacing in the strip in which they are provided, compensating adjustment may be made.

Another object of the invention is to so friction the work that it may be nicely controlled and will operate only under positive movement of some part which is designed for the purpose, thus preventing inertia from causing overtravel of the feeding.

Another object of the invention is to provide a means for controlling the work strip by advancing it against a frictional holding for nicely controlling the same.

A further object of this invention is to utilize a friction brake shoe for the work as a guide for the work as it passes through the mechanism.

Another object of the invention is to also utilize this brake shoe and guide as a stop for locating the wire to which the terminal is to be attached.

Another object of the invention is to provide a means for holding the brake shoe in raised operative position so that the work may be easily positioned or loaded into the mechanism at the time of starting the same.

Another object of the invention is to provide a lock for holding the brake shoe in raised inoperative position which lock may be easily and quickly released for dropping the brake shoe into engagement with the work.

Another object of this invention is to provide a simple but effective and yet accurate means for minutely adjusting with relation to the plunger the position of the rolling punch which crimps the terminal arms about a wire.

Another object of the invention is to provide a transparent guard over this plunger to prevent fingers of the operator from getting beneath the punch.

Another object of this invention is to provide a snap fastener means for positioning the transparent guard in place, thus permitting the guard to be easily and quickly removed for access to the plunger should occasion so require.

With these and other objects in view, the invention consists of certain novel features of construction as will be more fully described and particularly pointed out in the appended claims.

In the accompanying drawings:

FIGURE 1 is a side elevation partly in section illustrating the mechanism which is the subject of this invention;

2

FIGURE 2 is an end view thereof at the righthand end of FIGURE 1;

FIGURE 3 is a rear view or elevation of the mechanism;

5 FIGURE 4 is an exploded view of various parts of the feeding arrangement;

FIGURE 5 is a perspective exploded view of the brake shoe, back guide and wire stop which is assembled into a single operating unit;

10 FIGURE 6 is a perspective view illustrating the relationship of the terminal strip and the unit which guides and acts as a brake for the strip, also showing the relationship of the wire to these parts;

FIGURE 7 is a sectional view of a fragmental portion 15 of the machine at the location of the rolling punch looking in the direction shown in FIGURE 2 and illustrating the relationship of the rolling punches to the work;

FIGURE 8 is a fragmental view in section and substantially along the lines 8—8 of FIGURE 7;

20 FIGURE 9 is a sectional view through the locking pin;

FIGURE 10 is a perspective view of a strip of terminals which strip is fed through this machine; and

25 FIGURE 11 is a perspective view of a single terminal attached to a wire and acting as a terminal therefor.

In proceeding with this invention, I have provided a feeding mechanism which may be adjusted to locate the work feeding pawl longitudinally with reference to the work and have provided an operating cam which is in two parts so that these may be relatively moved for controlling the amount of feed of the work engaging pawl. I have also provided a brake engaging this cam so as to control the movement of the cam and feeding pawl and prevent overtravel in either direction making a positive operation of cam control applicable to the feeding mechanism. I have also controlled the work, consisting of a strip of terminals, by applying a brake or frictional device engaging this work. The engagement is at such a point that one surface of the brake shoe acts as a guide for directing the work in the machine, while another part acts as a stop to limit the insertion of a wire into a terminal for closing parts of the terminal on the wire. The parts of the terminal which are closed on the wire are engaged by a rolling punch mounted in a plunger. The shape of this punch is such as to cause a rolling of the arms of the terminal as the plunger descends, but in order to position the punch in the plunger for fine adjustment, the end of this punch is provided with an inclined surface diagonal to the length of the plunger with a member engaging this diagonal surface so that movement of this member in one direction or the other will control the longitudinal position of the plunger. In order that the operation of the plunger may be observed and yet the fingers of the operator prevented from getting beneath the plunger, I have mounted a transparent guard

45 in front of the plunger by means of snap fasteners so that it may be easily removed by pulling upon the guard or may be re-positioned by merely pressing upon the guard to force snap fasteners carried by the guard and by the frame at either side of the plunger into engagement.

With reference to the drawings 10 designates a base which is generally rectangular but comprises substantially two different thicknesses, the lower part 11 being one thickness while raised from this lower part there is a more elevated portion 12 comprising the rest of the base. The small raised portion of the base is recessed as at 13 (FIGURE 2) and into this recess a guideway 16 is located which has a guide groove 17 therein along which a strip of terminals may slide and be guided. This guide groove 17 has a flat bottom with the rear edge 18 raised therefrom while the front edge of the guide 19 is formed by a member 20 which is held onto the base by screws 21

which pass through edge slots 22 in the member 20 and are threaded into the base 12.

A vertical support 23 having a rearwardly extending L-shape lower portion is secured to the base so as to stand upwardly therefrom. One end of this support is enlarged as at 24 and recessed to provide guideways for three sides of the plunger 25 which will reciprocate vertically in this recess toward and from the base. Gibs 26 extend over the front part of the plunger slightly so as to provide a guide for the front or fourth surface thereof in its reciprocating movement. This plunger is a solid block of steel which is suitably recessed for purposes hereinafter described. This plunger has a channel 27 (FIGURE 2) cut in the rear surface thereof and an arm 28 having a tongue 29 enters this channel and is secured thereto by a screw 30. This arm 28 has a depending portion 31 which is turned at right angles to provide a portion 32 extending longitudinally of the mechanism which portion carries a roll 33 projecting rearwardly from the arm. The offset of this arm is sufficient to clear the upstanding support 23 in the reciprocating motion of the plunger. However, in order to permit the rearward extending portion 28 of arm 31 freedom of motion, a slot 34 is cut in this support.

A work strip of terminals such as 40 (FIGURE 10) is positioned in the channel 17 and is fed forward by a feeding mechanism designated generally 41 and shown exploded in FIGURE 4. A shaft 42 is mounted in a bearing opening 43 in the support 23 and carries on the forward side of the support 23 a hub 44 to which there is secured one part 45 of an arm which carries a feeding pawl. This part 45 is fixed to the hub by means of screws passing through openings 46 and entering threaded openings 47 in the hub 44. This hub engages a face of the support 23 so as to limit movement of the shaft 42 rearwardly of the support. This part 45 has a pair of abutment surfaces 48, 48' which extend from this part at generally right angles to its plate-like form. The other part of the pawl carrying arm is designated 49 and is shaped as shown in FIGURE 4. It has an opening 50 to receive the portion 42' of the shaft 42 on the forward side of hub 44 and an opening 51 to receive one of the abutments 48 while the other abutment 48' is located over the upper edge 52 of this arm part and in a position in line with the projecting corner 53 of the part 49. This part 49 is free to rock about the axis of shaft 42 on this portion 42' and is held in adjusted position relative to the arm part 45 by screw 54 passing through projection 53 and engaging abutment 48' and screw 55 passing through opening 56 in the part 49 and projecting into opening 51 and against abutment 48. Springs 57 encircle each of these screws. Since the screw 54 will engage the abutment 48' and the screw 55 will engage the abutment 48 by screwing in one screw 54 and backing out the other screw 55 or vice versa, the relative position of the parts 45 and 49 comprising the pawl arm may be had, thus adjusting the position of the pawl relative to the work. The two arm parts 45 and 49 are held against axial separation by washer 58 and screw 59 which enters the threaded bore 60 in the end portion 42' of the shaft.

A pawl 61 is rockably mounted on screw 62 which passes through opening 63 in the pawl and into the threaded opening 64 in the lower portion of the arm part 49. This pawl is swung about this pivotal mounting by a spring 65 which engages a pin in opening 66 of the pawl and also hooks over the screw 55 on the arm comprising parts 45 and 49. A suitable washer 67 may be positioned between the pawl and the arm part 49 for locating the pawl in the correct position laterally of the work.

On the back side of the support 23, I have provided an oscillating mechanism which comprises a cam. This cam is formed in two parts, there being a part 70 having a hub 71 which engages the rear surface or a washer at the rear surface of the support 23 and through an opening

in this hub 71 the shaft 42 extends. This cam part is here shown as a generally rectangular plate about one-eighth of an inch in thickness. Also assembled on this shaft 42 there is a second cam part or plate 72 which is provided with openings 73 through which the shaft 42 extends. This cam part 72 is provided with slots 74 at either marginal end and through each of these slots a screw 75 extends which engages a washer 76 under its head while the screw passes into threaded opening 77 in the cam part 70. These two cam parts may be relatively adjusted within the limits of the slots 74 by loosening the screws 75 and adjusting the cam parts relative to each other. The location of these two cam parts is such that the roller 33 above described carried by the plunger will engage both cam parts as it is moved upwardly and downwardly as may be seen in FIGURE 3, and from this figure, it will be observed that as the plunger is moved downwardly it will engage the cam part 72 to turn the shaft 42 in one direction whereas if it is moved upwardly, it will engage the cam part 70 to move the shaft in the other direction. The cam part 70 is secured to the shaft 42 by means of a screw 71' which engages the shaft 42 and holds it fixed thereto.

In order to control the rotation of the cam and prevent it from overtravelling as a result of the movement imparted thereto by the roller 33, I have provided a brake shoe 80 having an opening through which the reduced portion 42'' of the shaft 42 extends and a friction face 81 to engage the surface of the cam part 72 so that when pressed by means of a washer 83 and helical spring 84 which abuts against washer 85 and is held in place by a cotter pin or other means 86 (FIGURE 3), the brake shoe will press against the cam and control its movement permitting movement only where there is a positive actuation and then only the amount of the positive actuation. A slot 87 is provided in one end portion of the brake shoe 80 to receive a pin 88 projecting rearwardly from the support 23 so as to prevent the cam from rotating about the shaft 42''.

A unit performing several functions is provided for the terminal strip. This unit is shown in perspective in FIGURE 5 and in an exploded view and assembled in FIGURE 6. A lever arm 90 is provided with a pivot opening 91 through which pivot pin 92 (FIGURE 3) extends to pivotally mount the lever 90 in recess 93 (FIGURE 7) in the support 23 adjacent the path of the operating plunger. Near one end of the arm 90 there is a thickened or padded portion 94 and upon this portion I have assembled a bracket 95 by means of screws 96. This bracket has a downturned portion 97 the edge 98 of which is located above the pawl 61 and serves as a limit for swinging this pawl upwardly. Also assembled upon this downturned portion 97 there is a brake shoe 99 held thereto by means of screws 100. The lower edge 101 of this brake shoe engages the work, and by means of a spring 102, this assembly is forced downwardly about the pivot 92 so as to press the lower edge 101 of the shoe 99 against the work. The outside edge of this arm engages the upturned prongs or lugs 130 on the strip of terminal 40 and further guides the lateral position of the terminal strip in its passage through the machine, while the slight raised end portion 103 which is thinner providing shoulder 104 is in a position to serve as a stop for the insertion of a wire 132 upon which there is to be assembled the terminal. Should it be desired to hold this assembly of FIGURE 6 in raised position, it is merely necessary to engage the handle end 90' of the lever arm 90 and move this downwardly about the pivot 92 to a position sufficient to permit a spring actuated pin 105 (FIGURE 9) having a recess 106 to move outwardly under action of a spring 107 with its portion 105' over the upper edge of this is a lever 90 to hold the handle 90' down and the shoe 99 in raised position against the action of its spring 102. In this position the strip is then freed to be slid along its guide 17 into any required location. When it is desired to release this brake and guide

unit and permit it to again move into engagement with the strip, it is merely necessary to manually engage the end of pin 165 forcing it inwardly and permitting the handle end of the lever 90 under action of spring 102 to move upwardly into the recess 106 while moving its brake shoe 99 downwardly into engagement with the work.

The plunger carries two rolling punches 108 and 108' with notches 109, 109' for engagement with the lugs 131 and 130 of the terminal to be crimped about wire 132. These notches are substantially V-shape and the rolling punches are one back of the other, one for one set of lugs and the other for the other set of lugs. They are so spaced that each will be reciprocated in the path of movement as the strip is guided and fed along the guide channel. Also carried by this plunger there is a cutter 110 which is positioned to sever by removing connection 133 of the strip terminal which is attached to the wire as the rolling of the lugs about the terminal occurs.

The upper end of the rolling punches are inclined as at 112 (see FIGURE 1) so as to be at an angle to the longitudinal extent of the guideways 113 which mount these punches. Each of the punches is slotted longitudinally and a screw 114 threaded into the body of the plunger serves to hold the punch in adjusted position. However, a very fine adjustment may be had by reason of the cam member 115 which is located against the upper horizontal surface 116 of the recess in which the punches are located and between two screws 117 and 118, access to which is had from the opposite sides of the plunger so that by screwing in one screw and backing out the other the position of the cam 115, the lower edge of which engages the diagonal surface 112, may be adjusted to force the punches downwardly if moved to the right or permitting the punches to be moved upwardly if moved to the left. By this arrangement a very fine adjustment may be had for the rolling punches for holding them in position.

In order to prevent the operator from putting his fingers beneath the plunger as it is forced downwardly, I have provided a guard plate 120, this guard plate being formed of a transparent material such as methyl methacrylate which will permit a clear view to be had of the plunger and its punches as they descend upon the work. This guard plate is provided with a notch 121 (FIGURE 1) through which the wire to be assembled with the terminal may be positioned. The guard plate may be easily and quickly attached to the forward edge of the upstanding support 23 and at either side or over the gibs 26 by snap fasteners, the socket portions 122 of which are carried on the fixed part of the support and the stud portions 123 are carried on the guard plate 120.

In order to provide for replacement when wear may occur, the base is cut out as at 125 (FIGURE 1) and a block 126 is set into this base with a portion 127 (FIGURE 7) cooperating with the cutter and also portions 128 and 129 cooperating with the rolling punches for effecting the cutting off and rolling of the lugs of the terminal about its wire.

The terminals which are to be fed in this machine are in strip form as shown at 40 in FIGURE 10. Initial positioning of the strip in the guideway 17 is done manually with the unit shown in FIGURE 5 and illustrated further in FIGURE 6 in raised position. As soon as the

strips are correctly positioned and the machine adjusted for the particular spacing of the terminals of the strip, the operator pushes button 105 allowing the brake shoe 99 to engage the strip. He may then insert a wire 132 such as also illustrated in FIGURE 6 and the plunger may be caused to move downwardly and close the lugs 130 and 131 about the wire 132 and at the same time remove the connector strip 133 from between the end terminal and next terminal and thus sever it from the strip. The wire with its terminal attached may then be removed from the machine, and as the plunger is raised, the next terminal is fed into position by the roll 33 on arm 32 engaging the cam part 70 for such actuation. The attaching step may then be repeated as often as desired and the feeding of the strips will be automatically accomplished each reciprocation of the plunger.

I claim:

1. A feeding mechanism for terminals in strip form comprising a guideway for the strip of terminals, a pawl engaging the strip, an arm carrying said pawl, a shaft for mounting said arm, and means for oscillating said shaft, said arm comprising two parts mounted for relative movement about the axis of said shaft, means for fixing one of the parts to said shaft, the other of said parts mounting said pawl, and means for relatively moving said parts and holding them in adjusted position for varying the position of the pawl.

2. A feeding mechanism as in claim 1 wherein said means for relatively moving said parts comprises threaded means carried by one part and engaging the other part at one side of the axis of said shaft for relative rotation of the parts about said axis.

3. A feeding mechanism as in claim 1 wherein said means for relatively moving said parts comprises screws carried by one part and engaging the other part at either side of the axis of said shaft for relative rotation of the parts about said axis.

4. A feeding mechanism for terminals in strip form comprising a guideway for the strip, a shaft, an arm mounted on said shaft, a pawl carried by said arm engaging said strip, means to oscillate said shaft comprising a plate fixed to the shaft and presenting a surface extending radially of said shaft, and a brake having a face engaging said surface and resilient means urging said face against said surface.

5. A feeding mechanism for terminals in strip form comprising a guideway for the strip, a shaft, an arm mounted on said shaft, a pawl carried by said arm engaging said strip, means to oscillate said shaft and a brake to oppose the resulting oscillation of said shaft.
